UNITED STATES PATENT OFFICE.

HERMANN HOFFMEISTER, OF GLIERMARODE, NEAR BRUNSWICK, GERMANY, ASSIGNEE
TO GRIMME, NATALIS & CO., AKTIENGESELLSCHAFT, OF BRAUNSCHWEIG, GERMANY,
A CORPORATION OF GERMANY.

CALCULATING MACHINE.

Application filed April 1, 1925, Serial No. 19,937, and in Germany April 8, 1924.

My invention relates to improvements in calculating machines, and more particularly in the construction of the machine frame, and the objects of the improvements are to 5 provide a frame which can be manufactured at low cost, is light in weight, and requires little space so that it is adapted to accommodate a setting mechanism of large capacity. With these objects in view my invention 10 consists in the novel machine frame made from a blank of sheet metal bent upwardly at opposite sides to provide the side walls of the casing. In the preferred form the said sheet metal blank is made with a 15 straight portion disposed in front of the body portion and the side walls thereof to provide means for securing thereto the guide members for the slide or carriage of the machine.

20 For the purpose of explaining the invention an example embodying the same has been shown in the accompanying drawing, in which the same reference characters have been used in all the views to indicate corresponding parts. In said drawing,

Fig. 1, is an elevation of the frame looking from the front side of the machine,

Fig. 2, is an end view looking from the right in Fig. 1 and showing in addition certain parts of the mechanism,

Fig. 3, is a plan view showing the sheet metal blank from which the frame is made, and

Fig. 4, is a detail view showing the mechanism for transmitting the movement of the carriage to the single tooth wheel.

For the purpose of explaining the invention I have shown the same embodied in a calculating machine as in Fig. 2 and comprising a setting mechanism 1 adapted to be rotated from a machine crank 2 by means of gear wheels. One of said gear wheels as at 3 is secured to the shaft of the machine crank 2 and is adapted to rotate two revolutions counting mechanisms 7 and 8 through gear wheels 4, 5, 6, which mechanisms count the number of the revolutions of the setting mechanism 1. Each single tooth wheel 11 is longitudinally shiftable on the shaft 6, which upon rotation of the said shaft operates the revolutions counting mechanisms 7 and 8 through the gear wheels 9 and 10. Shifting movement is imparted to the single tooth wheel 11 from the carriage or slide

(not shown) having the registering mechanism mounted thereon. As shown in Fig. 4 the said carriage is provided with a rack 12 adapted to shift a rack 14 through the medium of a double toothed sector 13. The rack 14 is guided on the base plate of the machine, and it carries an arm 15 straddling the single tooth wheel 11 with its bifurcated top end. Thus the said single tooth wheel is shifted into position for acting on the numeral wheel of the revolutions counting mechanism corresponding to the lateral displacement of the slide.

The general construction of the machine is known in the art, and I do not deem it necessary to describe the same in detail.

The frame of the machine is made from a blank *a*, of sheet metal, such as steel, iron, aluminium or brass. The side walls *b* are provided by bending the lateral portions of the blank at right angles to the body or bottom *f*, and the feet are secured to the said bottom *f*. Preferably, the blank is formed with cut-out portions *d* located along the line of bending to enable the operation to be readily performed.

In front of the body portion *f* of the blank there is an offset substantially rectangular portion *g* which may project at one or both sides beyond the body portion *f*, and which is separated at its ends from the body portion by notches or cut-out portions *e* projecting inwardly beyond the line on which the walls *b*, *b* are bent. The said portion *g* provides the base for the guide way of the slide of the machine.

The blank is provided with suitable holes and cut-out portions providing bearings for shafts, rods and other parts of the mechanism of the machine.

I claim:

1. A blank for folding into a frame for a machine of the class described, the blank having holes to afford bearings for machine parts and spaced rows of openings, said rows of openings being arranged along fold lines for end portions thereof which constitute sides of the frame when joined, the blank having a portion disposed at an angle to said rows to constitute a base for another machine part, the blank being notched at the junction of said portion with the remainder of the blank and in line with both rows of openings.

2. A blank for folding into a frame for a machine of the class described, the blank having holes to afford bearings for machine parts and spaced rows of openings, said rows 5 of openings being arranged along fold lines for end portions thereof which constitute sides of the frame when joined, the blank having a portion disposed at an angle to said rows to constitute a base for another machine part, one end of said portion intersecting the line of one of said rows and the blank having a notch also intersecting said line at the junction of said portion with the remainder of the blank.

3. A frame for a machine of the class described made from a blank and having a body, sides rising from the body having holes therethrough to afford bearings for machine parts, a portion at one edge of the body at an angle to said sides to form a base for a 20 machine part, the frame having rows of openings along the junction lines of the body and sides, and notches along said lines at the junction of the said portion and said body.

In testimony whereof I have hereunto set my hand.

Dr. Ing. HERMANN HOFFMEISTER.
